COMBINED SOUNDING HAMMER AND BLADE

Robert L. Angles, 9147 Valley Blvd., Rosemead, Calif.

Filed Feb. 1, 1965, Ser. No. 83,641

Term of patent 14 years

(Cl. D54—13)

FIG. 1 is a side elevation of the combined sounding hammer and blade showing my new design;

FIG. 2 is a plan view thereof;

FIG. 3 is a left end elevation thereof;

FIG. 4 is a right end elevation thereof; and

FIG. 5 is a bottom plan section taken along line 5—5 of FIG. 3.

The side not shown is similar to the side illustrated.

I claim:

The ornamental design for a combined sounding hammer and blade, as shown and described.
